UNITED STATES PATENT OFFICE.

LEIF LEE, OF YOUNGSTOWN, OHIO.

PICKLING MACHINE.

Application filed September 9, 1924. Serial No. 736,717.

To all whom it may concern:

Be it known that I, LEIF LEE, a citizen of the United States, and a resident of Youngstown, in the county of Mahoning and the 5 State of Ohio, have made a new and useful Invention in Pickling Machines, of which the following is a specification.

This invention relates to pickling machines and more particularly to an improved 10 form of mechanism for supporting and agitating articles in a pickling bath.

Pickling machines, as heretofore constructed, generally consist of a vertically reciprocating plunger having a spider at the 15 top, the arms of which extend outwardly over the pickling and washing baths. Containers, ordinarily termed trays, for the articles to be pickled, are supported from the arms of the spider. The plunger is lowered 20 to immerse the articles in the bath and is then reciprocated to agitate the articles therein, various types of mechanisms being used to control the operation of the plunger. This type of machine is somewhat complicated 25 in structure, due to the necessity for such devices as fluid pressure pumps, valves and the like, and, consequently, is expensive both to construct and operate.

An object of this invention is to provide 30 a simplified and improved form of mechanism for supporting and agitating articles in a pickling bath, which is rugged but at the same time an improvement both from the standpoint of structure and operation.

35 A further object is to provide a mechanism for the purpose set forth which can be directly operated from any convenient power shaft and in which such operating devices as air pumps, valves, storage reservoirs and the like are entirely eliminated.

These and other objects which will be apparent to those skilled in this particular art are attained by means of apparatus embodying this invention, one form of which is 45 shown in the accompanying drawings, in which—

Figure 1 is a plan view and Fig. 2 is a side elevation of the illustrated embodiment.

The particular embodiment of this invention, chosen for illustration, includes an oscillatory shaft which is supported adjacent one or more pickling baths. A pair of spaced walking beams is mounted on this shaft, and the beams are adapted to recipro-

cate supports on which trays are so supported that they are submerged in the pickling or washing solution. The supports are so constructed and arranged that the trays may be readily and easily suspended from them, and they are also of such character 55 that the oscillatory movement of the walking beams is imparted to the trays as a vertical reciprocatory movement.

The drawings show two pickling baths 5 and 6 which are supported in any desired 60 manner upon a suitable base 7. Bearings 8 and 9 are mounted in spaced relation between the pickling baths on a suitable standard 10, which is mounted on the base 7 between the baths 5 and 6, and extends above 70 the surfaces of the baths. A shaft 11 is journaled for oscillatory movement in the bearings and the shaft is provided, at its outer ends, with parallel arms or walking beams 12 and 13.

75 Each end of each walking beam is connected by means of a link 14 to a slide block 15 mounted in vertical guideways 16. Each slide block has an inwardly facing pocket 17 formed in the top thereof for receiving 80 one end of a rod 18 which supports a tray 19 in such a position that it is submerged by the liquid contained in the bath. As illustrated, each set of guideways 16 is mounted on one end of one of the baths, although it 85 will be apparent that the guideways may be independently supported adjacent the ends of the baths.

Each rod 18 has a collar 20 adjacent each 90 end thereof on which are formed lugs 21 and 22. Springs 23 and 24 are secured to the lugs, and cables 25 and 26 which support the trays are secured to the lower ends of the springs 23 and 24, respectively.

95 Agitation of the articles in the pickling solutions is obtained by oscillating the shaft 11 through the medium of a crank arm 27 which is shown in Fig. 2 as forming a part of the walking beam 12 but which may obviously be separately formed and connected 100 to the shaft 11 in any desired manner. A connecting rod 28 connects the outer end of the crank arm with a crank 29 formed on any desired power shaft 30. The shaft 30 may be driven from any convenient source 105 of power such, for example, as an electric motor 31, the shaft 32 of which drives the shaft 30 through the medium of worm wheel

33. The power shaft 30 may be provided with a clutch 34 for disconnecting it from the motor at any time.

In operation, the tray 19 is positioned in 5 a pickling bath by lowering the supporting rod 18 into the pockets 17 formed in the tops of the slide blocks. Any suitable form of overhead crane may be used for this purpose. Rotation of the shaft 30 oscillates the 10 shaft 11 so as to agitate the articles in the bath and at the end of the operation the rod 18 and container 19 may be lifted out of the bath and transferred where desired. The springs 23 and 24 prevent undue jarring of 15 the articles in the container and accentuate the motion transmitted to the container by the oscillating shaft. It is obvious that the trays on opposite ends of the walking beams counterbalance each other and that a 20 minimum amount of power is expended in operating the apparatus. In addition, the trays are reciprocated vertically while in the bath solution and this eliminates splashing and slopping of the solution. The apparatus 25 may also be applied to many standard forms of pickling and washing baths, thus eliminating the necessity for specially constructed baths.

Although I have described in detail but 30 one embodiment of my invention, I do not wish to be limited to the specific structure shown but what I claim as new and desire to secure by Letters Patent is:

1. The combination with a pickling bath, 35 of an oscillatory shaft, parallel arms secured to said shaft, a reciprocating member secured to one of said arms at each side of said bath and means for detachably supporting a container on said member for immersion in 40 said bath.

2. The combination with a pickling bath, 45 of a vertically reciprocating slide-head above each end of said bath, pockets formed in said slide-heads, means for detachably supporting a container from said pockets for immersion in said bath, an oscillatory shaft positioned adjacent said bath, and means for reciprocating said slide-heads from said shaft.

50 3. The combination with a pickling bath, of a vertically reciprocating slide-head mounted adjacent each end thereof, pockets formed in said slide-heads, means for detachably supporting a container in said 55 pockets for immersion in said bath, an oscil-

latory shaft positioned adjacent said bath and parallel arms secured to said shaft and connected to said slide-heads.

4. The combination with a pickling bath, of an oscillating member mounted above said bath, slide-heads adapted to reciprocate above said member, and means for yieldingly supporting a container from said slide-heads for immersion in said bath.

5. The combination with a pickling bath, of an oscillatory member mounted above said bath, a slide-head at each end of said bath adapted to be reciprocated by said member, a pocket formed in each slide-head, a rod adapted to be removably seated in said pockets and yielding means for supporting a container from said rod for immersion in said bath.

6. The combination with two pickling baths, of an oscillatory shaft positioned between said baths, a slide-head at each end of each bath, parallel walking beams secured one at each end of said shaft for reciprocating said slide-heads, a pocket formed in the top of each slide-head, and means for supporting a container in each bath from the pockets of the associated slide-heads.

7. The combination with two pickling baths of an oscillatory shaft positioned between said baths, a slidehead positioned above the end of each of said baths, parallel walking beams secured one at each end of said shaft for reciprocating said slideheads, a pocket formed in the top of each slidehead and means for resiliently supporting a container from the pockets of adjacent slideheads at each end of said beam for immersion in said baths.

8. The combination with two pickling baths of an oscillatory shaft positioned between said baths, a slide-head positioned above the end of each of said baths, parallel walking beams secured one at each end of said shaft for reciprocating said slide-heads, a pocket formed in the top of each slide-head, a rod adapted to extend longitudinally above each bath and to rest in the pockets of the associated slide-heads and means for resiliently supporting a container from each of said rods for immersion in the associated bath.

In testimony whereof, I have hereunto subscribed my name this 4th day of September, 1924.

LEIF LEE.
